UNITED STATES PATENT OFFICE

156,709

CAP GRIPPER

John Drazick, Detroit, Mich.

Application December 6, 1947, Serial No. 142,998

Term of patent 14 years

(Cl. D44—29)

To all whom it may concern:

Be it known that I, John Drazick, a citizen of the United States of America and residing at Detroit, county of Wayne, State of Michigan, have invented a new, original, and ornamental Design for a Cap Gripper, of which the following is a specification, reference being made to the accompanying drawings, forming part thereof.

I claim:

The ornamental design for a cap gripper, substantially as shown.

JOHN DRAZICK.
